UNITED STATES PATENT OFFICE.

EGBERT B. BROWN, OF MAYWOOD, ILLINOIS.

INVALID AND OPERATING BED.

SPECIFICATION forming part of Letters Patent No. 781,328, dated January 31, 1905.

Application filed January 16, 1903. Serial No. 139,276.

To all whom it may concern:

Be it known that I, EGBERT B. BROWN, a citizen of the United States, residing at Maywood, in the county of Cook, in the State of Illinois, have invented certain new and useful Improvements in Invalid and Operating Beds, of which the following is a specification.

This invention relates to improvements in beds intended for hospitals and sick-rooms and designed with various adjustments, comforts, and conveniences which are particularly useful in such situations.

The invention contemplates the use normally, though not necessarily, of a woven-wire mattress and the provision in connection with the mattress of additional springs by which it is bodily supported and given a resilient bearing independent of any spring action in the mattress itself; also, that the mattress shall be capable of being raised and lowered bodily and secured in any desired position of adjustment throughout a wide range of movement, and that it may be tipped or raised more at the head than at the foot, or vice versa, so as to arrange the bed upon an inclination in either direction as desired.

The invention also contemplates that the bed shall be provided with means for easily raising and lowering the mattress or either of its ends and locking it in place in the desired position of adjustment; also, that the bed shall be provided with various attachments—such as a footboard, a table, and an overhead support—by which the patient may assist himself in turning or in various ways, all of which tend to greatly increase the comfort of the person occupying the bed.

All of these improvements, together with various details of construction, I have fully set forth in the following specification in connection with the accompanying drawings, in which—

Figure 1 is a sectional side elevation of an invalid and operating bed constructed in accordance with my improvements. Fig. 2 is a top plan view thereof. Fig. 3 is an end elevation thereof. Fig. 4 is a sectional detail taken on line 4 of Fig. 2. Fig. 5 is a detail of one of the guide-rod-supporting clamps. Fig. 6 is a side elevation of the bed with the

table in place. Fig. 7 is a similar view of the bed with the foot-piece in place and with the mattress raised to an inclined position. Fig. 8 is a perspective detail of the foot-piece. Fig. 9 is a perspective detail of the overhead supporting-frame. Fig. 10 is a perspective detail of the table for the bed.

The frame of my improved bed thus illustrated may be constructed like that of any ordinary metal bed and is herein shown as comprising a head-piece H and a foot-piece F, connected by angle-iron side rails B. These head and foot pieces are each composed of corner-posts p, connected by transverse angle-irons A and by any suitable sort of grille-work G.

Within the bed-frame a mattress M is mounted to move vertically upon guide-rods R of the frame. Preferably and as herein shown this mattress is of that familiar construction comprising side rails m and end bars e, over which a sheet of woven wire w is tightly stretched. The mattress is, however, additionally provided with apertured corner-pieces m', that embrace the guide-rods R and slide up and down upon them. These guide-rods are herein shown as supported directly from the corner-posts p, being rigidly fastened to said posts at their lower ends by two-part clamps C, through which bolts are passed, and at their upper ends by eyebolts I, the sleeve portions of which embrace the guide-rods R, while their shank portions i extend through the corner-posts and are adjustably secured thereto by nuts z'. 85

The mattress is resiliently supported upon the guide-rods R by coiled springs S, provided on the lower ends of the rods. Loosely-fitting collars or rings r rest upon these springs and in turn support the corner-pieces m' of the mattress, the apertures m² of which are made only wide enough to freely embrace the guide-rods and too narrow to slip down over the collars. These apertures m² are, however, made considerably larger than the diameter of the guide-bars, so that they can be tipped at an angle thereto, and thus the mattress may not only be raised horizontally to the tops of the guide-rods to render the bed more convenient for surgical operations or otherwise, 90 95 100

but either end alone of the mattress may be raised to bring it into an inclined position—such as those shown, for example, in Figs. 1 and 7—and to support the mattress in this raised position the collars r are provided with thumb-screws r' , by which they may be clamped tightly upon the guide-rods, so as to prevent the mattress from dropping until the screws are again loosened.

- 10 To enable the mattress to be lifted more conveniently, cables L are shown as made fast at l to the end bars e of the mattress and are extended thence upwardly and downwardly around pulleys l' , secured to the top and bottom A of the head and foot pieces. The free ends of the cable are then made fast to hooks l'' and serve when so fastened to hold the mattress in the desired position of adjustment. When either cable is loosened from the hooks, 15 the mattress may be raised by pulling on the one end or may be lowered by pulling on the other end of the cable, as desired, its action being to lift the mattress off the springs or force it down upon and compress the springs, 20 as the case may be.

The length of the mattress in my improved bed will be made great enough to accommodate the tallest of persons, and then to furnish a convenient rest for the feet of the occupant, 25 whether tall or short, it is provided with an adjustable footboard F . (Better shown in detail in Fig. 9.) This footboard is provided with vertical telescopic standards f , having thumb-screws f' , by which the board may be 30 adjusted up and down, and the lower ends of these standards are furnished with foot-pieces, which are adapted to fit over and slide upon the side rails of the mattress and be clamped thereon by thumb-screws f'' .

- 35 40 For the convenience of the occupant also an adjustable table T is furnished, this table consisting of a table-top t , pivotally supported at t' upon vertical telescopic standards t'' , so that it can be swung to any desired angle, as indicated in dotted lines in Fig. 6. Thumb-screws t'' on the telescopic standards enable the height of the table to be adjusted, while its position upon the bed can be varied by sliding the standards along upon the side rails B of the 45 bed-frame, said standards being provided with feet t^4 , which fit upon these rails, and with thumb-screws t^5 , by which they may be clamped upon the rails at any desired point in the length of the bed.

- 50 55 A further attachment of convenience is also herein shown in the form of an overhead supporting-frame comprising adjustable telescopic standards O , having feet o adapted to fit the side rails of the bed and be clamped thereto by set-screws o' . These standards are joined at the top by a transverse supporting-bar O' , from which hand-rings H are suspended at the end of short ropes h . By grasping these rings the occupant of the bed may raise 60 himself bodily, so as to turn or change his

position without the assistance which would otherwise be necessary. A hook h' on the side of the support can also be used to suspend the water-bag of a fountain-syringe in case it becomes necessary to use the latter. It will be 70 apparent that an invalid and operating bed constructed after the manner thus described will be in the highest degree convenient and satisfactory for use in hospitals and sick-rooms. Owing to its spring-support, the bed 75 will be exceedingly comfortable for the patient when in use as an ordinary bed, while at any time the head or foot of the mattress may be raised, so as to support the patient in an inclined position, should he so prefer or should the necessities of his case demand it. For surgical operations and examinations the mattress can be raised to the height of an operating-table, and after the operation or examination is completed it can be lowered again to 80 the usual bed-level without any shock or jar to the patient. The raising of the mattress can be accomplished by two or more attendants lifting it from each side or by a single attendant using the cable l , and in either case 85 when raised to the desired position the bed can be locked securely in place by turning up the set-screws in the collars r . Under any circumstances the footboard may be adjusted along the length of the mattress to any position required by the size or posture of the patient, and food, medicines, reading matter, and the like may be readily supplied to the patient by placing them upon the table T , which can be also adjusted to suit the occasion. For heavy patients also and in cases 90 where sufficient assistance is not always at hand the provision of the overhead supporting-frame, by which the patient may himself move or turn over when otherwise comparatively helpless, will be found of greatest convenience.

One particular advantage of the constructions herein shown and described is that an ordinary bed-frame may be quickly fitted 100 with the improvements shown without the aid of skilled labor or in the least marring or changing the ordinary metal bedstead. The mattress-frame and its coöperating adjuncts may be kept in stock by dealers to be furnished private households when occasion requires, being substituted or used in lieu of the mattress sold with the bedstead.

It will be observed that by the construction shown and described the mattress-frame may 110 be raised bodily to points above the head-frame and pulled down against the action of the springs S to points below the bed-frame and locked at any point desired. By pulling the mattress-frame down below the side rails 115 B of the bed-frame said side rails serve as guard-rails to keep the patient from falling off the mattress, and by providing means whereby the mattress-frame may be lowered to or 120 nearly to the floor the danger of the patient 125

tossing off the mattress and injuring himself by falling to the floor is entirely avoided, while at the same time it permits the patient to be readily transferred to the floor or a mattress or stretcher on the floor adjacent to the bed.

I claim as my invention—

1. In a bed of the class described, the combination of a bed-frame, vertical guide-rods within the corners of the frame and extending above and below the rails of the bed-frame, a mattress-frame provided with apertured corner-pieces engaging and movable on said guide-rods, springs on the guide-rods beneath the corner-pieces to resiliently support the mattress-frame, and means for elevating the mattress-frame and also pulling it down against the action of its springs and for locking it in its adjusted positions.

2. An invalid and operating bed comprising a bed-frame, vertical guide-rods within the corners of the frame, said guide-rods being detachably attached to the corner-posts of the bed-frame, a mattress-frame provided with apertured corner-pieces fitting over and movable on said guide-rods, the apertures in said corner-pieces being long enough to permit the mattress-frame to be tipped into an inclined position, springs on the rods below the mattress-frame for resiliently supporting the same, and means carried by the bed-frame for independently raising and pulling down the opposite ends of the mattress-frame and locking them in their adjusted positions.

3. In a bed of the class described, the combination of a bed-frame, vertical guide-rods within the corners of the frame and extending above and below the rails thereof, a mattress-frame having apertured corner-pieces engaging said guide-rods, said apertures being long enough to permit the mattress to be tipped into an inclined position, springs on the rods beneath the mattress-frame for resiliently supporting the mattress, pulleys l' on the bed-frame above and below the side rails thereof, a pair of cords L attached to each end of the mattress-frame and one being carried up over the upper pulley and the other downward under the lower pulley and the free ends of the cords being adapted to be attached to the bed-frame to lock the mattress in its adjusted positions, the upper cord serving to lift the mat-

tress-frame and the lower cord serving to pull it down against the action of the supporting-springs, substantially as described.

4. An invalid and operating bed comprising 55 a frame, vertical guide-rods within the corners of the frame and extending above and below said frame, a mattress-frame provided with apertured corner-pieces fitting over and movable on said guide-rods, and springs provided on said guide-rods beneath the corner-pieces to resiliently support the mattress, substantially as described.

5. An invalid and operating bed comprising 65 a frame vertical guide-rods within the corners of the frame and extending above and below said frame, a mattress-frame provided with apertured corner-pieces fitting over and movable on said guide-rods, springs on said guide-rods beneath the corner-pieces, and movable 70 collars on said guide-rods between said springs and corner-pieces, substantially as described.

6. An invalid and operating bed comprising 75 a frame, vertical guide-rods within the corners of the frame and extending above and below said frame, a mattress-frame provided with apertured corner-pieces fitting over and movable on said guide-rods, springs on said guide-rods beneath the corner-pieces, movable 80 collars on said guide-rods between said springs and corner-pieces, and means for clamping said collars in adjusted position upon the guide-rods, substantially as described.

7. An invalid and operating bed comprising 85 a frame, vertical guide-rods within the corners of the frame, a mattress-frame provided with apertured corner-pieces fitting over and movable on said guide-rods, springs provided on said guide-rods beneath the corner-pieces to resiliently support the mattress, the apertures in said corner-pieces being long enough 90 to permit the mattress to be tipped into an inclined position, substantially as described.

In testimony that I claim the foregoing as my invention I affix my signature, in presence of two subscribing witnesses, this 7th day of January, A. D. 1903.
